UNITED STATES PATENT OFFICE.

FULTON W. SMITH, OF HILLSIDE, NEW JERSEY, ASSIGNOR TO COLGATE & COMPANY,
OF JERSEY CITY, NEW JERSEY, A CORPORATION OF NEW JERSEY.

DESIGN FOR AN ATOMIZER OR SIMILAR ARTICLE.

Application filed December 14, 1927. Serial No. 24,477. Term of patent 14 years.

To all whom it may concern:

Be it known that I, FULTON W. SMITH, a citizen of the United States of America, and a resident of Hillside, Union County, New Jersey, whose post-office address is 1 Wyndmoor Avenue, Hillside, New Jersey, have invented a new, original, and ornamental Design for an Atomizer or Similar Article, of which the following is a specification, reference being had to the accompanying drawing forming part thereof.

Figure 1 is a side view showing my design.
Figure 2 is a front view showing my design.

Figure 3 is a top view showing my design.
I claim:

The ornamental design for an atomizer or similar article, substantially as shown.

Dated at Jersey City, New Jersey, this 19th day of November, 1927.

FULTON W. SMITH.
